UNITED STATES PATENT OFFICE.

ALFRED G. F. KUROWSKI, OF BROOKLYN, NEW YORK, ASSIGNOR TO UNDERWOOD ELLIOTT FISHER COMPANY, OF NEW YORK, N. Y., A CORPORATION OF DELAWARE.

TYPEWRITING MACHINE.

Original application filed October 31, 1924, Serial No. 746,951. Divided and this application filed December 16, 1926. Serial No. 155,321.

This invention relates to improvements in typewriting machines, and more particularly to certain features of attachments for converting typewriting machines into 5 stencil-cutters, and for other purposes, in order to increase their range of usefulness.

The main feature of this invention is the provision of a typewriting machine having a mechanism for compensating for the 10 weight of the different devices which may be attached to the shift-frame of the machine without affecting the depression of the shift-keys.

The stencil-attachment illustrated and described herein will serve to demonstrate the utility of the invention. The attachment includes a stationary frame fastened to the platen-frame by means of easily accessible fasteners, and a swinging frame pivoted at 20 a point upon the fixed frame to the rear of the machine, and is provided with clamping jaws for first gripping a stencil-card by its upper margin, and then presenting the stencil to the printing field. The stencil-carrying frame shown in this connection is arranged to be lifted to line-space the stencil by means of a turning knob operating a cam-and-ratchet mechanism co-operating with means supported by the carriage to 25 feed the stencil step by step to the printing line.

It is customary in typewriting machines to normally operate the typewriter in lower-case type and to lift the platen to upper case 35 by the direct depression of a manually-operable key against the weight of the platen-frame and attachments thereon. Generally a counterbalancing spring is provided to aid in raising the platen-frame. Said 40 spring should be comparatively weak so that the platen-frame may be restored to lower-case type by gravity against the tension of the spring.

It will be apparent that if the counterbalancing spring is adjusted for compensating for the weight of the shift-frame without any attachment thereon, and then the weight of an attachment is added to the shift-frame, the full weight of the attachment 45 will have to be lifted by the shift-key, and consequently will make the key-depression hard and greatly hamper the operation of the machine.

In order to improve this condition, read-

ily accessible means are provided in the machine for effectively tensioning the shift-key spring and thus overcoming the added weight of the attachment.

In the patent to Sterling Elliott, No. 1,378,771, of May 17, 1921, there is disclosed a stencil-device built into a typewriting machine. The present invention illustrates an analogous device, in the form of an attachment which may be easily and quickly attached to and detached from a typewriter, 65 and consequently will enable the operative to alternatively use the typewriter either for ordinary typing without the attachment or with the attachment thereon as a stencil-cutter. This necessitates having accessible 70 adjusting means for quickly increasing or reducing the degree of compensation required, without inconvenience.

On the other hand, it may be desirable to add to the stencil attachment another device, 75 such as a collating table; or a different and possibly heavier stencil-device may be bodily substituted on the machine. To these ends, the shift-spring in the machine may be readily adjusted at one end for the various weights of the different attachments by changing the point of actuation of said spring, while means are also provided for stretching the spring by its other extremity 80 when the attachment is placed on the machine and for releasing the same when the attachment is removed.

This is a division of my application, Serial No. 746,951, filed October 31, 1924 (now Patent No. 1,621,074, dated March 15, 90 1927).

Other features and advantages will hereinafter appear.

In the accompanying drawings,

Figure 1 is a transverse section of the carriage and the platen-shifting mechanism of a typewriting machine, and shows the features embodying the present invention applied to the machine including the stencil-device shown in operating position and the shift-spring under tension to support the added weight of the attachment.

Figure 2 is a side elevation of the typewriting machine, showing the stencil-device removed from the machine, and includes the shift-mechanism showing the shift-spring released.

Figure 3 is a transverse section of the

typewriter-carriage and the stencil-device, showing means for supporting and feeding a carbon-strip around the platen.

Figure 4 is a side view of a detail, showing the shift-frame and a lever tensioning a spring operatively connected to the shift-frame.

Figure 5 is a plan view of a detail, showing the shift-frame and a lever tensioning a spring operatively connected to the shift-frame.

Figures 6 and 7 are fragmentary side views in elevation of the shift-frame and show a variation of means for tensioning and releasing the shift-spring.

Figure 8 is a detail, cross-sectional view on the line 8—8 of Figure 6, showing a supporting member for the lever and spring illustrated in Figures 6 and 7.

Figures 9, 10, 11 and 12 are modifications, showing the different relative positions of the shift-spring tensioning and releasing lever.

Referring to Figures 1 and 2, wherein a portion of a typewriting machine is shown, 25 20 represents the machine-frame, and 21 indicates a type-bar pivotally mounted to swing and strike a platen 22, which is revolvably mounted on a shaft 23 and is supported at the ends by platen-frames 24.

Typewriting machines are provided with mechanism for automatically lifting the ribbon and interposing the same between the type and the work-sheet, and for silencing 35 said mechanism when cutting stencil-blanks. Said ribbon-lifting mechanism should be silenced previously to operating the machine for stencil-cutting.

For supporting a stencil-card 25, there is 40 mounted upon a shaft 26 a plurality of clamping jaws 27, manually operable by means of a finger-piece 28 and a thumb-piece 29. In order to insert the card 25, the stencil-frame is first swung rearwardly on 45 a rock-shaft 30, the finger-piece 28 and the thumb-piece 29 are pressed together to open the jaws 27, and the card may be inserted and gripped between the jaws. For holding the stencil-card 25, which may be of a 50 different width, the jaws 27 are provided with depressions 87 for locating the wider cards, and with a screw 85 which may be used for locating the narrow card as shown in Figure 3.

The stencil-card 25 is guided while the 55 stencil-frame moves to a typing position, as shown in Figure 1, by means of a deflector-plate 31 which is permanently fastened to the typewriter-frame and comprises a series of guide-lines to enable the operative to 60 properly locate the card in printing position, and is also provided with elongated slots (not shown) to render said plate relatively adjustable to the printing line, in order that a comparatively fine adjustment 65

may be obtained. Said deflector-plate 31 may be permanently fastened to a type-bar-segment 32^a of the typewriter to replace the usual wing-scale. Heretofore it has been customary to remove the deflector-plate used 70 in connection with a stencil-device and substitute for the same the regular wing-scales for typing. In order to eliminate the objection of removing the plate when transforming the machine, the deflector-plate 31 75 is designed so that it may be used both when typing or when using the typewriter with the stencil-attachment. To this end, the plate 31 is provided with a series of guidelines on the outwardly-extending pieces 78, 80 and is bent out at the ends, forming ears 79 for guiding the stencil-card when letter-feeding the same. It is also provided with outwardly-extending bends 83 at its uppermost edges to assist in guiding the stencil-card when entering the printing position. In order that the plate 31 may tend to bear 85 lightly on the platen 22, the plate is fastened to the typewriter by means of two downwardly-extending fingers 84 which form a resilient connection between the plate and the platen, thus effectively holding against the platen of the machine either the work-sheet or the stencil-card.

The stencil-card 25, while held by the 95 clamping jaws 27, may be moved vertically, step by step, for spacing the several lines of an address, and, for this purpose, a line-spacing means, as shown, is arranged for manual operation. The line-spacing means 100 comprises a roller 37, mounted on the fixed frame of the stencil-device, and serves as a supporting member for a cam 33, manually operable by means of a finger-wheel fast 105 upon a shaft 34, and journaled in side plates 36, rigidly connected by a cross-bar 88 and a tie-rod 101, and pivoted on the rock-shaft 30. Said cam 33 is made with varying radii, so that as it is turned, the frame-bars and the clamping jaws, supported thereby, will 110 be raised to and held at different elevations, to correspondingly vary the elevation of the stencil-card. Means are associated with said shaft 34 by which it is arranged to be held against reverse rotation and also in several 115 different angular positions to predetermine the position of the lines. Said means, as here shown, consists of a wheel 90 arranged for connection with the shaft 34 and for moving ratchet-teeth 91 arranged to be engaged by a detent 92, on an arm 93, which is loosely pivoted at 94. Said detent-arm has a limited movement only on its pivot by reason of the slotted end portion 95 engaging a pin 96. The detent acts to hold a 120 ratchet-toothed wheel 100 in any position in which it may be set, by the rotation of shaft 34, but permits turning in one direction only. The teeth on said wheel are arranged in groups, shown as three in num- 125 130

ber, and each group has a different number of teeth. This provides for varying the number of lines, and also for spacing the lines more or less widely apart.

- 5 After the stencil has been impressed by the type and it is desired to remove it from the clamping jaws, the members 28 and 29 controlling the same are operated, and, by means of a link 97, operatively connected to 10 the detent-arm 93, by means of a pin-and-slot arrangement 98, when the clamping jaws are operated to remove the impressed card, the link 97 is swung upwardly due to its being connected to the jaws 27 at 99, thereby 15 lifting the detent 92 to clear the short teeth in the wheel 91, and permitting a spring (not shown), within the wheel 90, to return the cam to its original or starting position, against a large tooth of the wheel 100. 20 Means are also provided to make carbon-type-impressions on the backs of the stencil-cards, so that the type-impressions may be visible at the front of the stencil-cards. To this end, there are shown in the drawings 25 two different methods of feeding and supporting a carbon-strip 38 around the platen 22. Figure 1 shows a carbon-paper-receptacle 39, mounted on a bracket 102, and having a slot 40 through which the paper is 30 threaded from a roll of carbon-paper 41, and the strip 38 is wound around the platen 22. For locating the carbon-strip there are provided the end covers 103.

For supporting the carbon-strip 38 on the 35 platen 22, there is provided a roller 76 manually releasable by means of a handle 77, and operatively mounted upon a tubular member 47. Said tubular member 47 is mounted on a shaft 67, which also serves as 40 a tie-rod for the platen-frames 24. Paper-fingers 82 of the typewriter are mounted on the rod 48, and may be thrown back as shown in Figure 1, previously to the attaching of the stencil-device to the machine. 45 Normally, when the stencil-device is on the machine, the roller 76 is held for bearing against the platen 22, in known manner, by means of a spring mounted on member 47, and concealed thereby from view. The lateral 50 movement of the tubular member 47 is limited in relation to the shaft 67, in order that, when the stencil-device is attached to the machine, the roller 76 will be approximately located in relation to the platen 22.

55 Figure 3 shows another method of supporting and feeding the carbon-strip 38, in which a roll of carbon-paper 42 is mounted on a shaft 43, fed around the platen 22 and wound again on a spool 44. In order to 60 tension the carbon-strip 38, a spring-plate 45 is mounted on a supporting shaft 46 bearing on the paper-roll 42 and the spool 44 and providing an equal and uniform tension on both ends of the strip 38. The two 65 shafts supporting the rolls of carbon-paper

and the shaft 46 are mounted on side plates 89, which are fastened to the fixed frame of the stencil-device by means of the shafts 30 and 67.

It is customary to provide a back for the 70 stencil-cards, in order to prevent the type-blows from injuring the platen and to facilitate the cutting of the stencil. A backing 52, generally made of celluloid or other hard material, is held on the platen 22, at the 75 point where the carbon-strip 38 passes around the same, encircling the platen 22 and being held in place thereon by means of a holder-plate 53. Mechanism including a pair of pins 54, carried by one end of the 80 platen 22, engages notches 55 in a stop-device 56 when the platen is turned and limits the movements thereof. The stop-device 56 is fast upon the stencil-frame, and will consequently be withdrawn when the 85 stencil-device is removed from the machine, thus permitting the unobstructed operation of the platen 22.

In order to render the stencil-device detachable from the typewriting machine, 90 there is provided on the platen-frames 24 a plurality of fasteners and two locating plates 58 adjustably mounted on the stencil-side-frames 59. Said plates 58 are provided with elongated slots 60 for straddling the 95 shaft 48, and are adjustably fastened to the frames 59 by means of screws 80, to permit the stencil-devices to be adjusted in relation to the platen 22 of the typewriter. Paper-guide 104 is shown mounted upon a shaft 100 105 for the purpose of illustrating a clearance cut 106 in the side frames 59, necessary to clear said shaft 105.

Normally a spring 61 is adjusted to counterbalance the typewriter-platen-frame for 105 use without any attachment thereon, and consequently the tension of said spring will have to be increased proportionally to compensate for the added weight of the stencil-attachment, or the extra weight would have 110 to be lifted by the pressure on the shift-key which would make the depression hard, the inner extremity of the shift-key-lever 49 being secured as usual to the shift-frame 62. In order that the key-depression may be 115 light, regardless of the weight of the attachment on the platen-frame, means are provided to manually tension the spring 61 for effectively compensating for the added weight of the attachment. Referring more 120 particularly to Figures 1 and 2, which show an over-center-spring arrangement, the spring 61 is fastened to the shift-frame 62 at one end while the other end is operatively connected to crank 63, operable by means of 125 a handle 64. The handle 64 may be under tension as shown in Figure 1 and held against a stop 65 on the machine-frame. The spring tension may be released by swinging the handle 64 to a position as 130

shown in Figure 2. A variation of the mechanism described is illustrated in Figures 4 and 5, in which corresponding reference numerals are shown.

- 5 It is desirable to provide means for compensating for the weight of the several attachments which may be placed on the machine, of which one may be considerably heavier than the other. To this end the 10 spring 61 may be fastened to any of a plurality of notches 66 in the shift-frame 62, thereby increasing or decreasing the leverage or radius of action of the spring 61 to suit the weight of the different attachments. 15 In addition to the adjustment for controlling the tension of the spring 61 at one end, there is provided at the other end a lever 68 to temporarily stretch the spring for compensating for the weight of an attachment 20 on the machine. A perforated plate 69, fast on the frame 20, is designed to co-operate with an interposing member 71, which may arrest the advancement of the lever 68 as shown in Figure 7. By placing the member 25 71 in different holes 70, the initial tension of the spring 61 may be changed to suit the weight of the attachment. In order to increase the tension of the spring 61, the lever 68 may be swung so that its back will be 30 arrested by the same interposing member 71.

A variation of the above method for manually increasing or decreasing the tension of the spring 61 is shown in Figures 9, 11 and 12, in which a plurality of holes 72 in 35 a plate 73 are designed to support an interposing member 74 and to arrest the travel of a lever 75 controlling the stretch of the spring 61, as shown in Figures 11 and 12. To release the spring 61, the lever 75 is 40 swung to a position as shown in Figures 9 and 10. The adjustment at the other end of the spring 61 is obtained by means of the same notches 66 in the shift-frame 62.

Variations may be resorted to within the 45 scope of the invention, and portions of the improvements may be used without others.

Having thus described my invention, I claim:

1. In a typewriting machine, the combination with a carriage and a shiftable platen therefor, a shift-frame operatively connected to said platen, a shift-key and a shift-lever for manually operating said shiftable platen, of a spring operatively connected with said 50 shift-frame for effectively compensating for the weight of the platen-frame, there being means at one end of the spring for changing the point of actuation relatively to the fulcrum of the shift-frame; means including at 55 the other end of the spring an over-center swinging crank for effectively stretching and holding said spring under tension, and means concentric with said crank for directly operating said crank, by swinging the same over 60 dead-center at will.

2. In a typewriting machine, the combination with a carriage and a shiftable platen therefor, a shift-frame operatively connected to said platen, a shift-key and a shift-lever for manually operating said shiftable platen, 70 of a spring operatively connected with said shift-frame for effectively compensating for the weight of the platen-frame, there being means at one end of the spring for changing the point of actuation relatively to the fulcrum of the shift-frame; means operatively connected to the other end of said spring including an over-center swinging crank, fastened to a manually-operable lever which is operatively mounted upon a perforated 80 supporting plate, the perforations in said plate co-operating with an interposing member therein, in order to obstruct and thereby arrest the travel of said lever for rendering the initial tension of the spring adjustable. 85

3. In a typewriting machine, the combination with a carriage and a shiftable platen therefor, a shift-frame operatively connected to said platen, a shift-key and a shift-lever for manually operating said shiftable platen, 90 of a spring operatively connected with said shift-frame for effectively compensating for the weight of the platen-frame, there being means at one end of the spring for changing the point of actuation relatively to the fulcrum of the shift-frame; means at the other end of the spring for effectively stretching the same in definite steps, including a plate fast on the machine-frame, a swinging crank having a large radius of swing and an independent handle for operating said crank arranged concentrically therewith and rotatably mounted on said plate, said plate having a plurality of holes therein and an independent interposing member co-operating therewith, the position of the member being changeable into the different holes for obtaining a variable stretching of the spring, and means for releasing the spring by 105 swinging the handle away from the interposing member. 110

4. In a typewriting machine having a vertically shiftable platen-frame, the combination with a detachable paper-handling unit mounted on said frame and shiftable 115 therewith, and a rail-frame for shifting said platen-frame, of a counterbalancing spring mechanism for the platen and shift-frames, including a member directly shiftable from normal low-tension position to opposite 120 high-tension position when the aforesaid unit is attached to the platen-frame.

5. In a typewriting machine having a vertically-shiftable platen-frame, the combination with a detachable paper-handling 125 unit mounted on said frame and shiftable therewith, and a rail-frame for shifting said platen-frame, of a counterbalancing spring mechanism for the platen, and rail frame, including a relatively-rigid stop on said ma- 130

- chine, a crank pivotally mounted on the machine in spaced relation to said stop, a spring connected at one end to said crank and at the other to the rail-frame, a pivot 5 for the crank, and means associated with said pivot, whereby to rotate said crank from a normal low-tension position of the crank and spring to an opposite high-tension position in order to counterbalance said detachable unit, said stop being disposed between the low and high tension positions of said pivot means.
6. In a typewriting machine having a main frame, a vertically-shiftable platen-frame supported thereon, and a rail-frame for shifting said platen-frame, the combination with a detachable paper-handling unit mounted on the platen-frame and shiftable therewith, of a counterbalancing device including a support on said main frame, a projecting stop on said support, a spring connected at one end to said rail-frame, a crank connected to the other end of said spring and pivotally mounted on said support in such manner as to be swingable over dead-center from an initial low-tension position of the spring in which the crank is disposed adjacent the stop upon one side, to a final high-tension position wherein said crank is disposed adjacent the stop on the other side in order to counterbalance said detachable unit, and distinct means to swing said crank at will.
7. In a typewriting machine having a main frame, a vertically-shiftable platen-frame supported thereon, and a rail-frame for shifting said platen-frame, the combination with a detachable paper-handling unit mounted on the platen-frame and shiftable therewith, of a counterbalancing device including a support on said main frame, a stop which is displaceable to various stationary positions on said support, a spring connected at one end to said rail-frame, a crank connected to the other end of said spring and pivotally mounted on said support in such manner as to be swingable over dead-center from an initial low-tension position of the spring in which the crank is disposed adjacent the stop upon one side, to a final high-tension position wherein said crank is disposed adjacent the stop on the other side in order to counterbalance said detachable unit, and distinct means to swing said crank at will.
8. In a typewriting machine having a main frame, a vertically-shiftable platen-frame supported thereon, and a rail-frame for shifting said platen-frame, the combination with a detachable paper-handling unit mounted on the platen-frame and shiftable therewith, of a counterbalancing device including a plurality of stop-seats upon said main frame, a detachable stop-member arranged to individually engage and be supported in said stop-seats, a spring connected at one end to said rail-frame, and a crank connected to the other end of said spring and pivotally mounted on the main frame in such manner as to be swingable over dead-center from any one of a plurality of initial low-tension positions of the spring in which the crank is disposed adjacent said stop-member upon one side, to a corresponding final high-tension position in which the crank is disposed adjacent the stop-member upon the other side, there being means to swing said crank at will.
9. In a typewriting machine having a main frame, a vertically-shiftable platen-frame supported thereon, and a rail-frame for shifting said platen-frame, the combination with a detachable paper-handling unit mounted on the platen-frame and shiftable therewith, of a counterbalancing device including a stationary stop on said main frame, a spring connected at one end to said rail-frame, a rotatable pivot mounted on the main frame, a crank-arm connected to the other end of said spring and secured to said pivot in such manner as to be swingable thereon over dead-center from normal low-tension position of said spring in which the crank-arm is disposed adjacent said stop upon one side, to an opposite high-tension position in which said crank-arm is disposed adjacent the stop upon the other side in order to counterbalance the weight of said detachable unit, and a manually-operable lever secured to said pivot, whereby to rotate the same and swing said crank-arm.

ALFRED G. F. KUROWSKI.
